UNITED STATES PATENT OFFICE.

WILLIAM ALEXANDER DICKIE, OF SPONDON, NEAR DERBY, ENGLAND, ASSIGNOR TO
AMERICAN CELLULOSE AND CHEMICAL MANUFACTURING COMPANY LIMITED, A
CORPORATION OF DELAWARE.

APPARATUS FOR COATING WIRE WITH VARNISH AND THE LIKE.

Application filed January 10, 1922. Serial No. 528,816.

To all whom it may concern:

Be it known that I, WILLIAM ALEXANDER DICKIE, a subject of the King of Great Britain, of Spondon, near Derby, England, have invented certain new and useful Improvements in Apparatus for Coating Wire with Varnish and the like, of which the following is a specification.

This invention consists of improvements in apparatus for coating wire with dope, varnish or similar preparations, more especially for electric insulating purposes, and relates to apparatus of the kind in which the wire, after passing through a bath or supply of the liquid coating preparation, travels on through a device for removing surplus coating preparation therefrom.

The invention is particularly intended for coating bare wire with viscous insulating dopes or varnishes of cellulose acetate or other cellulose derivatives dissolved in volatile solvents without or with plastifiers or other additions. For such purposes it is very important that the coating applied to the wire shall be very even and uniform in thickness.

This result is attained by the present invention by means of a rotary tubular doctor, through which the wire carrying the liquid coating material passes up axially and centrally, the surplus removing orifice of the rotary tubular doctor surrounding and being coaxial with the wire travelling through it.

In combination with the said rotary tubular doctor disposed coaxially with the line of travel of the wire and having its surplus removing orifice surrounding and coaxial therewith, I may employ immediately above it a tube, passage, or chamber hereinafter referred to as an evaporation controlling chamber which is adapted to enable the dope or preparation carried by the travelling wire to evaporate in an atmosphere containing volatile solvent liberated from the dope or preparation on the wire, and thereby prevents too rapid evaporation and irregular setting of the coating on the wire. The said tube or passage may be unheated, or if desired it may be heated. Means may be provided for priming the evaporation-controlling tube, passage or chamber with solvent vapour at the commencement of working or for keeping it replenished with solvent va-

pour during working. Such means may for example consist of needle-valve controlled container discharging into the tube, passage or chamber; or an annular or other trough may be provided at the bottom of the tube, passage or chamber and be filled with liquid volatile solvent, or both such means may be provided. The wire may if required pass on from the evaporation tube, passage or chamber through a heated tube or chamber, in order to drive off any remaining volatile solvent and dry off the coating.

The accompanying drawings illustrate by way of example two forms of wire coating apparatus constructed in accordance with the invention.

Fig. 1 is a sectional side elevation of the coating and evaporation devices according to one form, and Fig. 2 is a front elevation thereof.

Figs. 3 and 4 are similar views of another form of apparatus.

Referring first to Figs. 1 and 2, 1 indicates a lower vessel containing a cellulose acetate dope to be applied to the wire. The wire W is led from a reel 2 over a guide pulley 3 on the bath and round a guide pulley 4 immersed in the dope, and then travels upward through a vertical tubular doctor 5 mounted above the container, the upper orifice of this doctor being restricted so as to remove surplus dope and leave a sufficient quantity on the wire for the required thickness of coating. The doctor tube is accurately centered so that the wire passes centrally up through it, and it is provided with a cord pulley 6 for rotating it at a suitable speed (e. g. about 1500-2000 R. P. M.) about its axis with a view to neutralizing any eccentricities in the orifice and for facilitating equal distribution of the dope around the travelling wire by the restricted orifice of the doctor. It is possible that the viscous dope or coating preparation may creep or flow slowly down the travelling wire after this has passed up through the doctor, but it is found that by rotating the doctor as referred to, a sufficiently even coating may be obtained on the wire. Also the return of the surplus dope removed from the wire to the container may be facilitated by the rotation of the doctor tending to throw it back into the container. Above the doctor 5 is mounted a vertical tube made in two sec-

tions 7-7^a, preferably divided by a partition 8 with a central orifice 8^a for the passage of the wire, and the top end of the portion 7^a is also preferably closed except for 5 a central opening 9 for the passage of the wire. The upper tube or chamber 7^a is heated by a steam coil 12 or otherwise for the purpose of drying out remaining solvent as the wire travels on. After leaving 10 the tube 7^a the wire passes on over a pulley 13 and is finally wound on a wind-up reel 14. The reels 2 and 14 may be driven by any convenient means.

It will be seen that the coating on the wire 15 travelling up through the tube 7 can evaporate in an atmosphere containing vapour or solvent liberated therefrom, too rapid evaporation and too rapid shrinkage of the coating on the wire being thus prevented.

20 10 represents a small container for liquid solvent (e. g. acetone) which may be provided for priming the tube 7 with vapour at the commencement or for keeping the tube replenished with volatile solvent during working, this container discharging into 25 the upper part of the tube 7 and its delivery being controlled by a needle valve 10^a. An annular trough 11, formed in the bottom of the tube 7 by an upstanding annular lip 11^a 30 surrounding the nozzle of the doctor, is also shown as provided for the priming or replenishing of the tube with vapour, 11^b being an overflow from the trough.

Any number of doctors and tubes such as 35 described may of course be arranged in line, or be otherwise grouped, to deal with any desired number of wires, which may be led through a common coating bath and thence up through the doctors and tubes.

40 Referring now to Figs. 3 and 4, these illustrate another form of apparatus in which a single evaporation-controlling and drying arrangement common to a number of rotary doctor tubes is employed for dealing with the wires issuing from the doctor tubes. 15 indicates the coating bath disposed below a row of doctor tubes 5 driven by cord pulleys 6, the wires W being led from wind-off reels 2, over guide pulleys 3 45 on the bath, round guide pulleys 4 in the bath and thence up through the doctor tubes 5 similarly to the previous arrangement. The evaporation-controlling and final drying chambers in this construction are constituted by a casing of flat, box-like form, divided into a lower section 16 and an upper section 16^a by a partition 20 formed with slots or holes for the passage of the wires, similar slots or holes being likewise provided in the closed top of the upper chamber 16^a which is heated by steam pipes 17 controlled by valves 18. The wires W from the doctor tubes pass up through holes in the bottom of the evaporation-controlling chamber 16 common to all the wires, travel

through this chamber and the upper steam heated chamber 16^a, thence over the guide pulleys 13 and are wound up on the reels 14. Any desired number of vessels 10 may be fitted to the chamber 16 for priming or 70 replenishing the same with solvent vapour. A trough 19 for the solvent is also shown as formed at the bottom of the chamber 16, the holes for the passage of the wires being shown as formed with upstanding lips or 75 flanges to permit of this, 19^a is the trough overflow.

If desired any known or suitable means may be provided for conveying away and recovering the solvent vapours from the 80 tubes 7-7^a or chambers 16-16^a.

It is of course to be understood that the particular apparatus described and illustrated are given only by way of example and may be varied considerably without departing from the invention.

The evaporation controlling tube or chamber and the final drying tube or chamber may be made separate and distinct from each other. Or they may open freely into each other or form one tube or chamber with its upper portion heated. Or the final drying tube or chamber may be dispensed with, the evaporation-controlling tube or chamber being heated or not. The evaporation-controlling tube or chamber and the final drying tube or chamber when employed, may of course be of any suitable cross section and dimensions according to the number and grouping of the doctor devices which they serve. Although it is much better to enclose the evaporation-controlling chamber or combined evaporation-controlling and final heating chamber for more efficiently attaining the result of enabling the coating to evaporate in the atmosphere of solvent liberated therefrom, and for recovering the solvent vapours, it has been found that it is possible to attain the evaporation-controlling effect even with an open evaporation-controlling tube or chamber by making this sufficiently long and small or narrow in section.

What I claim and desire to secure by Letters Patent is:—

1. In apparatus for coating wire with viscous insulating dope or varnish containing volatile solvent, the combination with means for supplying the liquid coating to a travelling wire, of a rotary tubular doctor disposed above the coating applying means co-axially with the line of travel of the wire, and having its surplus removing orifice surrounding and co-axial therewith, and means for rapidly rotating said tubular doctor about its axis.

2. Apparatus for coating wire with viscous insulating dope or varnish containing volatile solvent, comprising in combination a liquid coating bath, a rotary tubular

doctor disposed above said bath co-axially with the line of travel of the wire and having its surplus removing orifice surrounding and co-axial therewith, means for causing the wire to travel through said bath and up through said rotary tubular doctor, and means for rapidly rotating said tubular doctor about its axis.

3. Apparatus for coating wire with viscous insulating dope or varnish containing volatile solvent, comprising in combination a liquid coating bath, a rotary tubular doctor disposed above said bath coaxially with the line of travel of the wire and having its surplus removing orifice surrounding and co-axial therewith, an evaporation controlling chamber disposed above said rotary tubular doctor, means for causing the wire to travel through said bath and up through said rotary doctor and evaporation controlling chamber, and means for rapidly rotating said tubular doctor about its axis.

4. Apparatus for coating wire with viscous insulating dope or varnish containing volatile solvent, comprising in combination a liquid coating bath, a rotary tubular doctor disposed above said bath coaxially with the line of travel of the wire and having its surplus removing orifice surrounding and co-axial therewith, an evaporation controlling chamber disposed above

said rotary tubular doctor, means for causing the wire to travel through said bath and up through said rotary doctor and evaporation controlling chamber, means for supplying liquid volatile solvent to said evaporation controlling chamber, and means for rapidly rotating said tubular doctor about its axis.

5. Apparatus for coating wire with viscous insulating dope or varnish containing volatile solvent, comprising in combination, a liquid coating bath, a rotary tubular doctor disposed above said bath coaxially with the line of travel of the wire and having its surplus removing orifice surrounding and co-axial therewith, an evaporation controlling chamber disposed above said rotary tubular doctor, and a heated final drying chamber located above said evaporation controlling chamber, means for causing the wire to travel through said bath, rotary tubular doctor, evaporation controlling chamber and final drying chamber, and means for rapidly rotating said tubular doctor about its axis.

In testimony whereof I have hereunto subscribed my name.

WILLIAM ALEXANDER DICKIE.
